UNITED STATES PATENT OFFICE

156,566

VENDING MACHINE

Jack H. Schmidt, Chicago, Ill., assignor to The
Northwestern Corporation, Morris, Ill.

Application December 28, 1948, Serial No. 150,407

Term of patent 14 years

(Cl. D52—3)

To all whom it may concern:

Be it known that I, Jack H. Schmidt, a citizen of the United States, and resident of Chicago, in the county of Cook and State of Illinois, have invented a new, original, and ornamental Design for a Vending Machine, of which the following is a specification, reference being had to the accompanying drawings, forming a part thereof:

Fig. 1 is a front elevational view of a vending machine, showing my new design and with the glass globe shown in broken outline;

Fig. 2 is a side elevational view of the same with the glass globe again shown in broken outline; and

Fig. 3 is a top plan view of the same.

The side of the vending machine not shown and the rear thereof are substantially plain.

The essential features of my design reside in the portions shown in solid lines.

I claim:

The ornamental design for a vending machine, substantially as shown and described.

JACK H. SCHMIDT.
